JAMES HULSE HUMPHRIES, OF WESTMINSTER, LONDON, ENGLAND.

MEANS FOR DRIVING SCREW FILES AND CYLINDERS.

Application filed January 4, 1926. Serial No. 79,278.

This invention relates to improvements in means for driving screw piles and cylinders, and refers particularly to means of the type in which a framework carries a power unit or units with reduction gearing transmitting the power to a central rotatable member which receives or engages the head of a pile or cylinder to be driven. The weight of the framework and mechanism is supported by the pile or cylinder during the driving operation, and rotation of the framework relative to the pile or cylinder is prevented by suitable anchorage ropes or cables.

In driving piles or cylinders of large diameter, an enormous torque has to be applied, and in machines as hitherto employed, where the head of the pile, or of an adaptor to engage the head of the pile or cylinder, is received in a chuck member in the axis of the rotatable central member of the machine, this torque has to be applied at a very short radius. The driving torque to the rotatable member on the other hand is usually applied through gearing to gear teeth on the periphery of the rotatable member which is normally of large diameter, and there is thus a heavy bending moment applied to the spokes or arms of the rotatable member, and the parts of the chuck are under severe shearing stress.

The object of my invention is to provide an improved machine in which these heavy bending and shearing stresses are practically eliminated, so that the danger of fracture of parts in use is removed and the general construction can be considerably lightened.

The manner in which these objects are attained will be apparent from the description below with reference to the accompanying drawings in which:

Figure 1 is a plan showing the arrangement of the power units and gearing.

Figure 2 is a longitudinal vertical section through the axis of the central rotatable member.

Figure 3 is a plan of one half of the central member with an adaptor in position.

Figure 4 is a section on the line 4—4 of Fig. 3.

In the arrangement illustrated, the power units consist of two similar electric motors *a*, symmetrically disposed on opposite sides of the centre of the machine. Each motor shaft through a coupling *b* drives a worm meshing with a worm wheel in a casing *c*. On the shaft of the worm-wheel is a pinion *d* meshing with a gear wheel *e*, and on the shaft of this wheel is a further pinion *f* meshing with gear teeth on the periphery of the central rotatable member or wheel *g*. The gear-teeth are preferably of the double-helical type.

The method of mounting the wheel *g* is shown in Fig. 2. The wheel is secured upon the lower end of a tubular sleeve *h* which is rotatably mounted in flanged bushes *j* secured in the framework *k*. Floating oil rings *l* interposed between the sleeve and the bushes are adapted to take any wear, and can be readily renewed. The vertical thrust between the wheel and the framework when screwing piles or cylinders is taken by the annular shoulder *m* on the wheel. Preferably a shoulder *n* is also provided on the sleeve to take the thrust when screwing piles of small diameter of which the upper ends fits within the lower end of the sleeve which may be squared to receive them.

The wheel *g* is formed in two parts, the outer rim which carries the gear-teeth being bolted to the main body of the wheel. In the rim adjacent to the teeth are formed recesses *g'* to receive upstanding bosses *o'* on a hollow truncated conical adaptor *o* having a flange at its lower end to which the upper end of a cylinder to be screwed is adapted to be bolted as shown in Fig. 2. The adaptor has to support the weight of the machine when a cylinder is being screwed and is therefore stiffened against vertical thrust by radial ribs *o*². It will readily be seen that the torque required to rotate a cylinder bolted to the lower end of the adaptor is transmitted through the adaptor from the bosses *o'* which are engaged by the wheel at a radius little less than that of the pitch circle of the gear teeth. Thus the bending moment on the wheel is practically negligible, and the central parts of the wheel are relieved of all stress so that the wheel and its mounting can be made very much lighter than in the usual type of construction. Another form of adaptor and an alternative means for connecting the adaptor to the wheel are illustrated in Figs. 3 and 4.

Connection between a cylinder and the wheel *g* is made through an adaptor *p* of truncated inverted conical outline with an annular flange *q* at its lower end to which the cylinder is adapted to be bolted.

The upper end of the adaptor has a number of segmental upstanding members *r*

which are adapted to enter segmental openings *s* in the wheel adjacent to its periphery. The members *r* are of hollow box section for lightness and the inner and outer curved walls are connected by radial ribs *t* to give rigidity. The inner walls of the members *r* lie against an annular upstanding rib *u* on the wheel, and the adaptor is bolted to the wheel at intervals to support the weight of the adaptor. These bolts do not, however, take any of the torque as this is taken between the ends of the members *r* on the adaptor and the ends of the openings *s* in the wheel. Stiffness in an axial direction is given to the adaptor by inclined radially directed ribs *v*, *w*, integral with the side walls of the adaptor and with the bottom flange *g* and with the members *r*.

The construction of the wheel itself will be obvious from Figs. 3 and 4. The rim which carries the gear-teeth *x* and in which are formed the openings *s* is carried by substantial spokes or arms *y* from a central boss which is rotatably supported in the machine as described with reference to Figs. 1 and 2.

I claim:—

1. A machine for driving screw cylinders, comprising a frame, self-contained power means carried by the frame, a peripherally toothed wheel member rotatably mounted on said frame, reduction gearing between the power means and the wheel member, and means for connecting the wheel member to a cylinder to be driven at a radius substantially equal to the radius at which the drive is applied from the gearing to the wheel member.

2. A machine for driving screw cylinders comprising a frame, self-contained power driving means carried by the frame, means for rotatably supporting a peripherally toothed wheel member centrally in the frame, reduction gearing connecting the power driving means to the wheel member, and an annular adaptor connecting the wheel member adjacent to its periphery to a cylinder to be driven.

3. A machine for driving screw cylinders, comprising a frame, self-contained power driving means carried by the frame, means for rotatably supporting a peripherally toothed wheel member centrally in the frame, reduction gearing connecting the power driving means to the wheel member, and a truncated inverted conical adaptor keyed at its upper end to the wheel member adjacent to the periphery thereof, and having means at its lower end by which it can be connected to a cylinder to be driven.

4. A machine for driving screw cylinders comprising a frame, self-contained power driving means carried by the frame, means for rotatably supporting a peripherally

toothed wheel member centrally in the frame, reduction gearing connecting the power driving means to the wheel member, and a truncated inverted conical adaptor, which is to be connected at its lower end to a cylinder to be driven, and at its upper end has upstanding segmental parts entering within complementary segmental openings in the wheel member adjacent to the periphery thereof.

5. A machine for driving screw cylinders comprising a frame, self-contained power driving means carried by the frame, means for rotatably supporting a peripherally toothed wheel member centrally in the frame, reduction gearing connecting the power driving means to the wheel member, and a truncated inverted conical adaptor, which is to be connected at its lower end to a cylinder to be driven, and at its upper end has upstanding segmental parts entering within complementary segmental openings in the wheel member adjacent to the periphery thereof, the said segmental parts being of hollow box form, and having an inner wall which lies against, and is bolted to, an upstanding annular flange on the wheel member.

6. A machine for driving screw cylinders, comprising a frame, self-contained power driving means carried by the frame, means for rotatably supporting a peripherally toothed wheel member centrally in the frame, reduction gearing connecting the power driving means to the wheel member, and a truncated inverted conical adaptor having at its upper end upstanding segmental parts entering within complementary segmental apertures in the wheel member adjacent to the periphery thereof, and having at its lower end a horizontal flange to which a cylinder to be driven is bolted.

7. A machine for driving screw cylinders, comprising a frame, self-contained power driving means carried by the frame, means for rotatably supporting a peripherally toothed wheel member centrally in the frame, reduction gearing connecting the power driving means to the wheel member, and a truncated inverted conical adaptor having at its upper end upstanding segmental parts entering within complementary segmental apertures in the wheel member adjacent to the periphery thereof, and having at its lower end a horizontal flange to which a cylinder to be driven is bolted, the said adaptor being stiffened against axial thrust by integral radially directed ribs extending between the said segmental parts and the said bottom flange.

In testimony whereof I affix my signature.

JAMES HULSE HUMPHRIES.
